UNITED STATES PATENT OFFICE.

ABRAM H. JONES, OF HARTFORD CITY, INDIANA.

GAS-GENERATOR.

No. 822,132.

Specification of Letters Patent.

Patented May 29, 1906.

Application filed July 24, 1905. Serial No. 271,002

To all whom it may concern:

Be it known that I, ABRAM H. JONES, a citizen of the United States, residing at Hartford City, in the county of Blackford and State of Indiana, have invented certain new and useful Improvements in Gas-Machines; and I do declare the following to be a full, clear, and exact description of the invention, such as will enable others skilled in the art to which it appertains to make and use the same.

This invention relates to improvements in gas-machines.

The object of the invention is to provide a machine of this character in which gas may be produced from either oil or coal, or a combination of both.

Another object is to provide means whereby the gas produced in the generator may be thoroughly scrubbed and cleaned.

With the above and other objects in view the invention consists of certain novel features of construction, combination, and arrangement of parts, as will be hereinafter described and claimed.

In the accompanying drawings, Figure 1 is a perspective view of a gas-machine constructed and arranged in accordance with the invention. Fig. 2 is a longitudinal vertical sectional view of the same. Fig. 3 is a similar view of the generator and the centrifugal oil-injecting device, and Fig. 4 is a detail sectional view of the centrifugal oil-injecting device.

Referring more particularly to the drawings, 1 denotes the generator, which consists of a suitable receptacle, preferably formed of metal, which is lined with walls formed of fire-brick and is divided into end and centrally-disposed compartments by means of transversely-disposed partitions 2, which extend to the top of the dome or arch-shaped cover 3 of the generator. The end compartments 4 and 5 are generating-chambers, while the central compartment 6 serves as a mixing-chamber. In the end compartments adjacent to the partitions 2 are arranged breaker-walls 7, formed of fire-brick, said walls extending up toward the top of the body portion of the generator, thus leaving a space between the upper end of the same and the arch-shaped cover 3.

In the lower ends of the partitions 2 are formed a series of apertures *a* to permit the passage of the gas formed in the generating-chambers 4 and 5 into the mixing-chamber 6.

In the side walls of the generator-compartments 4 and 5 are formed suitably-closed manholes 8, and in the opposite ends of the same are formed inlet-holes into which pipes 60 9 are inserted and through which the gas-forming material is injected. The generator 1 is supported upon a suitable base or platform 10 and is supplied with heat in any suitable manner. As shown in Fig. 3, a hole *b* is 65 formed in the bottom of the generator to supply air thereto, and through this opening the spray of oil and steam is ignited.

Adjacent to one end of the generator 1 on the base 10 is arranged a supporting-bracket 7c 12, on which is disposed a centrifugal oil-injecting device 13, said device consisting of a cylindrical casing in which is revolvably mounted a turbine-wheel 14, above which and resting thereon is arranged a perforated 75 plate 15. In one side of the casing of the injector is arranged a steam-supply pipe 16, said pipe being connected to said casing at an angle tangent to the turbine-wheel, whereby the steam entering through said pipe will 80 strike the blades of said wheel and rapidly revolve the same. In the top of the casing is arranged an oil-supply pipe 17, through which oil is fed into the injector and onto the perforated plate therein. In the side of the 85 casing opposite to that having the steam-supply pipe is arranged a discharge-pipe 18, said discharge-pipe projecting through the inlet-hole of the generating-compartment 4, whereby the oil and steam from the centrifugal injector are introduced into said compartment in the form of a fine spray.

In the inlet-opening of the opposite generator-compartment 5 is inserted the nozzle 9a of a coal-injecting device. (Not shown.) 95 Said coal is fed into the compartment 5 in the form of a fine dust by means of steam or compressed air, and the coal being thus reduced to a powder is injected into the compartment in the form of a spray. As shown in 100 Fig. 3, a hole *c* is formed in the bottom of the generator to supply air thereto, and through this hole the coal-dust is ignited.

The gas when formed in the compartments at each end of the generator will be 105 drawn by suction over the breaker-walls 7 and through the openings *a* in the lower ends of the partitions 2 and into the mixing-chamber 6, where said gases are mixed and from which the same pass through a discharge-pipe 19, arranged on the arch-shaped cover of the generator, and from thence into

a receiving-box 20 of a wet scrubber 21. The wet scrubber 21 consists of a vertically-disposed cylindrical receptacle 22, on the upper end of which is arranged the receiving-box 20. In the bottom of the receiving-box 20 is arranged a perforated plate 23, and in the cover of the receiving-box is formed a water-inlet 24. In the receptacle 22 is arranged a centrally-disposed supporting-rod 25, on which is secured a series of circular disks or plates 26, said disks being spaced apart at suitable intervals in said receptacle. There may be any suitable number of the plates or disks 26, four of the same being 15 shown in the present instance. The two upper plates of said series are provided with perforations or apertures 27, the perforations of the upper plate being considerably larger than those of the lower plate. As the gas 20 passes into the receiving-box 20 of the scrubber and through the receptacle 22 water is forcibly sprayed upon the same through the inlet-opening 24.

In the bottom of the scrubber-receptacle 25 22 is arranged a discharge-pipe 28, which communicates with the lower end of a second wet scrubber 29, said second scrubber consisting of a cylindrical receptacle 30, arranged on the base 10 and having on its upper end a removable cap 31. In the receptacle 30 is arranged a water-supply pipe 32, on the end of which adjacent to the bottom of the receptacle 30 is arranged a perforated discharge nozzle or rose 33. The gas entering the lower end of the receptacle 30 passes upwardly through the same and through the spray of water from the nozzle 33 to a discharge-pipe 34, arranged in the receptacle 30 near the upper end of the same. In the lower end of the receptacles 22 and 30 are arranged drip-pipes 35, which project into drip-receptacles 36, arranged beneath the wet scrubbers, said receptacles 36 being connected by a pipe 37, and in one of the 45 same is formed an overflow-opening 28.

Arranged on the base 10 between the two wet scrubbers is a dry scrubber, said dry scrubber consisting of a cylindrical receptacle 40, having on its upper end a removable cap 41. In the receptacle 40, adjacent to the bottom of the same, is arranged a horizontally-disposed perforated partition-plate 42, below which in one side of the receptacle is connected a suction discharge-pipe 43, extending through a gas-compressor. (Not shown.) The upper end of the receptacle 40 is connected with the discharge-pipe 34 of the second wet scrubber, whereby the gas from the latter scrubber passes into the dry 55 scrubber and through a suitable cleaning and drying material in said receptacle. The drying and cleaning material contained in the dry scrubber may be of any suitable character, but is preferably formed of coke and ext-65 celsior.

From the foregoing description, taken in connection with the accompanying drawings, the construction and operation of the invention will be readily understood without requiring a more extended explanation. 70

Having thus described my invention, what I claim as new, and desire to secure by Letters Patent, is—

1. In a gas-machine, the combination with a supporting-base, of a generator arranged thereon, said generator having formed therein separate generating-compartments to receive oil and coal-dust, breaker-walls in said compartments, means whereby said oil is mixed with steam and injected into one compartment of said generator, means for the injection of said coal-dust into the generator, means for igniting said oil and coal-dust, means whereby the gas from said oil and coal-dust is mixed in said generator and a series of 85 scrubbers and purifiers arranged on said base to receive the mixed gas from said generator, substantially as described. 80

2. In a gas-machine, the combination with a supporting-base, of a generator arranged on 90 said base, said generator having arranged therein partitions to divide the same into generating and mixing compartments, breaker-walls in said compartments, means whereby oil and coal-dust are injected into 95 said generating-compartment in the form of a spray, the gas from said oil and coal being commingled in said mixing-compartment, wet scrubbers arranged on said base to receive the gas from said mixing-compartment 100 and a dry scrubber to receive the gas from said wet scrubbers, substantially as described.

3. In a gas-machine of the character described, the combination with a supporting-base, of a generator arranged thereon, said generator having arranged therein a dome-shaped cover, transversely-disposed partitions arranged in said generator to divide the same into generating and mixing compartments, said partitions having formed in their lower ends a series of apertures forming passages between the generating and mixing compartments, means for injecting oil, steam and coal-dust into said compartments, breaker-walls arranged in said generating-compartments adjacent to said apertured partitions, and extending only part way up in said compartments, whereby gas from the oil and coal in the latter may pass over said 115 walls and be drawn through the apertured partitions into said mixing-chamber, wet scrubbers arranged on said base to receive the commingled gases from said mixing-chamber and a dry scrubber to receive the 120 gas from said wet scrubbers, substantially as described. 110

4. In a gas-machine, the combination with a supporting-base, of a generator arranged thereon, said generator having formed there-130

in separate generating-compartments to receive fire, steam and coal-dust, means for injecting oil steam and coal-dust into said compartments, and mixing-compartment in which the gases from said generating-compartments are commingled, a centrifugal oil and steam mixing and injecting device adapted to spray oil and steam into one of said generating-compartments, wet scrubbers to receive the gas from said mixing-compartment, and a dry scrubber to receive the gas from said wet scrubbers, substantially as described.

5. In a gas-machine, the combination with a supporting-base, of a generator arranged thereon, said generator having formed therein separate generating-compartments to receive oil and coal-dust, and a mixing-compartment into which the gas from said generating-compartment is drawn and commingled, a centrifugal oil and steam mixing and injecting device to spray oil and steam into

one of said generating-compartments, said mixing and injecting device consisting of a cylindrical casing, a turbine-wheel revolvably mounted in said casing, a perforated plate arranged above said wheel, a steam-inlet pipe arranged in said casing tangent to said turbine-wheel, an oil-inlet pipe arranged in the top of said casing, and a steam and coal discharge pipe arranged in the side of the casing opposite to said steam-inlet pipe and in communication with one of the generating-compartments of said generator, and wet and dry scrubbers to receive the gas from the mixing-compartment of said generator, substantially as described.

15 In testimony whereof I have hereunto set my hand in presence of two subscribing witnesses.

ABRAM H. JONES.
